UNITED STATES PATENT OFFICE

ARTHUR GUY ENOCK, OF WEMBLEY PARK, ENGLAND, ASSIGNOR TO BURLECTAS LIMITED, OF LONDON, ENGLAND

APPARATUS FOR CLEANING BOTTLES

Application filed August 3, 1929, Serial No. 383,209, and in Great Britain August 27, 1928.

This invention relates to bottle washing apparatus in which the bottles are washed inside and/or outside while grouped or contained in crates.

5 The object of the invention is to construct a washing machine in which the bottles are scrubbed inside or both inside and outside while contained in the crates of known or ordinary or standard construction (not forming part of the machine) in which they are transported from place to place, without being inverted in the crate and without inverting or reversing the crate before or after the washing operation so enabling the brushing to be done while the bottles are full of water and dispensing with the use of water spraying brushes.

According to the invention the machine is constructed with brushes or scrubbing surfaces carried above the path of the crates in overhead rotary holders fitted with gears to rotate the brushes, a stationary runway and intermittently traversing conveyor chain upon which the crates rest and by which they are intermittently traversed through the machine, a number of cleft pedestals to enter the crates mounted upon a vertically reciprocating member or cross bar by which the bottles are automatically raised in the crates until they are partly or nearly above the top edges of the crate, a spring controlled bottle mouth guide against which when raised the bottle is held during the operation of scrubbing and a cam or its equivalent by which the reciprocating member and with it the bottles are raised into engagement with the brushes or scrubbing surfaces.

The invention will be fully described with reference to the accompanying drawings.

40 Fig. 1 is a longitudinal section of the machine showing the brushes or scrubbing surfaces B and B¹, the bottle mouth guides E and E¹, the conveyor H for traversing the crates C¹ and the lifting pedestals M and lifting cam K¹.

Fig. 2 is a transverse section similar to Fig. 1.

Fig. 3 is a plan of the rotary brush holders. 50 Fig. 4 is a section of a modification of lift-

ing member for washing the interior of a crate full of bottles.

Fig. 5 is a plan of same.

The machine is constructed with a casing or framing A supporting gear boxes D² which enclose the working parts at the top and depending therefrom, brushes or scrubbing surfaces B for the interior of the bottles C and brushes or scrubbing surfaces B¹ for the exterior of the bottles C which brushes are carried in rotary holders D, D¹ rotated by gears d, d¹ from a shaft d² driven by a motor N. The holders D of the interior brushes B are geared together by the gears d and the holders D¹ of the exterior brushes B¹ are geared together by the gears d¹, a continuous rotary movement being given to the brushes. The brush holders D, D¹ are enclosed in the gear boxes D². Adjacent to each of the interior brushes B, a spring controlled bottle mouth guide E is fitted which extends below the brush B and is adapted to rise vertically against the pressure of springs e on guide rods e¹ and adjacent to each set of the exterior brushes B¹ a spring controlled bottle mouth guide E¹ is mounted between the brushes and is adapted to rise vertically against the pressure of a spring e² on a guide rod e³ which latter when the bottle is raised projects into it. A rotary movement is also given to rod e³ and bottle mouth guide E¹ to rotate the bottle during the operation of scrubbing the exterior.

Motion is imparted to the rod e³ by a connecting bar F and cranks f driven from the shaft d² by worm and wheel f¹.

Stationary runways G, G¹ (preferably of angle iron) are placed at a convenient distance below the brushes B, B¹ with traversing chain conveyors H, H¹ upon which the crates C¹ full of bottles C are placed and traversed intermittently through the machine beneath the brushes. The chain conveyors H, H¹ are fitted with upstanding lugs g by which the crates are positioned thereon and the conveyors may extend at both ends of the machine to receive and deliver the crates and may be connected with other machines for treating or filling the bottles without removing or handling them. A second 10x

chain conveyor G^3 may be mounted at the delivery end of the machine to convey the crates quickly away. The conveyor centres the bottles in one crate under the interior 5 bottle brushes B and in the next crate under the bottle mouth guide E^1 and guide rod e^3 .

The chain conveyors H, H^1 are moved forward by sprocket wheels g^1 on the shaft g^2 to which an intermittent motion is imparted to 10 move the crates forward a distance equal to the width of one row of bottles at a time. The shaft g^2 is driven from the driving shaft K by known or suitable intermittent gearing (not shown) which will give the desired step 15 by step or intermittent motion to the conveyor chains and crates.

A number of cleft pedestals M are mounted in rows upon a vertically reciprocating transverse member or plate m below the path 20 of the crates C^1 on the conveyor chains H, H^1 . The pedestals M enter the bottom of the crates to raise the bottles a row at a time, the cleft or slot m^1 in the pedestal avoiding the wire in the bottom of the crate which supports 25 the bottles. The top of each pedestal is preferably dished or countersunk to facilitate the rotation of the bottle thereon during washing of the exterior. The transverse member or plate m is fitted with slides m^2 30 which slide vertically between guides m^3 provided with oil grooves for lubrication. It is raised intermittently by a cam K^1 on the driving shaft K timed to synchronize with the chain conveyors H, H^1 when the crates 35 C^1 and bottles C are at rest beneath the brushes B, B^1 . One row of pedestals raises a row of bottles for interior scrubbing while the other row of pedestals raises a row of bottles in an adjacent crate for exterior 40 scrubbing.

In the modification shown in Figs. 4 and 5 the transverse lifting member m^2 may carry a plurality of pedestals M^2 equal in number 45 to the full number of the bottles in the crate so that the interior scrubbing of all the bottles in the crate may be effected at the same time, a corresponding number of brushes being carried by the gear box. In this construction, the bottles are first raised by the pedestals 50 M^2 until the mouths of the bottles emerge from the top of the crate to engage with and take the weight of the bottle guides. When the bottles have been raised to this extent the member m^2 engages the crate and lifts 55 it with the bottles also lifting the frame of the bottle guides as the crate and bottles move up together until the brushes are inside the bottle to the necessary extent. During the whole of this operation the weight of the 60 bottles is carried by the pedestals M^2 and not by the crate or its wires.

Spraying jets (not shown) for spraying and filling the bottles with water as they enter the brushing machine are supplied and 65 other spraying appliances for spraying the

brushes and the outside of the bottles are also embodied but it does not appear to be necessary to specify these in more detail.

One of the special advantages of this machine, in addition to its being able to brush 70 bottles in crates and to convey them with a minimum of breakage and labour, is that the inside brushing of the bottles is done when the bottles are mouth up and contain water and the whole mass of water is revolved by 75 the brush and the scouring action of the water as well as that of the brush is secured. The scheme of the bottle mouth guide E is also a great advantage as it acts as a brush cleaner 80 in passing up and down the bristles as the bottles rise for brushing. This enables the brush to be kept very much cleaner than would otherwise be the case.

The scrubbing surfaces may be formed of 85 the usual fibre or bristle brushes but they may be formed of rubber sheets or pads provided with indentations, corrugations, projecting lines or projecting studs.

What I claim as my invention and desire to 90 protect by Letters Patent is:—

1. Apparatus for cleaning bottles in portable crates comprising means for conveying crates containing bottles through the machine, overhead brushes or scrubbing surfaces, reciprocating cleft pedestals to enter the bottom of the crates and by which bottles are automatically raised into contact with the brushes, and means for raising the pedestals. 95

2. Apparatus for cleaning bottles in portable crates comprising a stationary runway, 100 an intermittently traversing conveyor chain thereon upon which the crates rest and by which they are intermittently traversed through the machine, brushes or scrubbing surfaces above the path of the crates, overhead rotary holders by which the brushes or scrubbing surfaces are carried, a plurality of vertically reciprocating cleft pedestals to enter the bottom of the crates by which bottles are automatically raised in the crates into 105 contact with the brushes and spring controlled bottle mouth guides by which each bottle being scrubbed is held during the scrubbing operation and a cam to intermittently raise the pedestals and bottles the desired distance. 110

3. Apparatus for cleaning bottles in portable crates comprising a stationary runway, 115 an intermittently traversing conveyor chain thereon upon which the crates rest and by which they are intermittently traversed through the machine, brushes or scrubbing surfaces above the path of the crates to enter the bottles, other brushes or scrubbing surfaces above the path of the crates to contact with the exterior of the bottles, overhead rotary 120 holders by which the brushes or scrubbing surfaces are carried, a plurality of vertically reciprocating cleft pedestals to enter the bottom of the crates by which bottles are auto- 125

matically raised in the crates in contact with the brushes, spring controlled bottle mouth guides by which each bottle being scrubbed is held during the scrubbing operation and by which the brushes entering the bottles are cleaned and a cam to intermittently raise the pedestals and bottles the desired distance.

In testimony whereof I have hereunto set my hand this 18th day of July, 1929.

ARTHUR GUY ENOCK.
